ALFRED J. MURPHY, OF NEW YORK, N. Y.

DISPLAY CABINET FOR RUGS AND OTHER TEXTILE FABRICS

Application filed March 31, 1932. Serial No. 602,155.

This invention relates to a cabinet for facilitating display of rugs and other textile fabrics and has for its general object to select and exhibit a number of rugs from a quantity stored within a cabinet, so that the selected rugs may be compared with each other to assist a prospective purchaser in deciding which one to buy.

Heretofore in displaying rugs for sale they were usually arranged in piles on the floor and the salesman and an assistant usually took hold of the opposite corners of each rug and turned it half over on the pile, to exhibit the various rugs one after another. This procedure requires considerable time and labor and cannot permit of arranging a number of selected rugs in a row to be seen at one time for comparison.

The present invention aims to do away with the disadvantages of the previous cumbersome method of handling and displaying rugs and in providing a more convenient, modern and sanitary method.

To these ends the invention further consists in the novel details of construction and combination of parts more fully hereinafter described and particularly pointed out in the claims.

Referring to the drawings forming a part of this specification, in which like numerals designate like parts in all the views:—

Figure 1 is a perspective view of the display cabinet with a number of rugs shown for display therein.

Figure 2 is a vertical broken longitudinal sectional view of the cabinet on an enlarged scale.

Figure 3 is an enlarged longitudinal sectional view taken through the upper right side end portion of the cabinet, at right angles to Figure 2.

Figure 4 is a cross-sectional view taken on the line 4—4 of Figure 3, looking in the direction of the arrows, and

Figure 5 is a cross-sectional perspective view of one side of the cabinet taken on the line 5—5 of Figure 2.

Referring to the drawings in details the cabinet 1 is formed of L-shaped skeleton steel frame construction 2 to provide a horizontal

display section 3 and a vertically arranged display section 4. These sections are left open at their top 5 and front 6 respectively, and are enclosed at their sides 7 and 8, front 9, back 10, top 11 and bottom 12 by either wood or sheet metal to provide a casing as shown. The vertical section 4 is divided by a central partition 13 (see Fig. 2), to provide a front display section 14 and a rear storage section 15. Within the opposite sides of the vertical section of the frame, at the lower front portion is mounted a series of drive shafts 16 and in the upper front and rear portions of the frame is also mounted a series of shafts 17 and 18. On each of the shafts is mounted a pair of sprockets 19 located adjacent the ends of the shafts.

Mounted within the casing is a plurality of rug carriers 20, each of which is formed of a pair of chains 21 arranged on the opposite side ends of the carrier for travelling over the sprockets 19 mounted in the upper end of the casing and under the sprockets 19 mounted in the lower end of the casing. The chains are connected by a series of spaced cross-bars 22 (see Fig. 3) which are in turn connected to each other by a series of spaced metal strips 23 to provide a means for preventing the rug from sagging between the bars when the rug is secured to the carrier. The ends of the cross-bars project through the chains to provide bearings for rollers 24, which are adapted to travel in channel guide bars 25 secured to the inner opposite sides of the horizontal and vertical sections of the frame. These guide bars are provided for guiding the rug carriers in their path of movement through the cabinet and for supporting the rug carriers when in the horizontal section of the casing, as shown. The rugs 26 are mounted on the carriers in extended position and are secured to the outer surface of the carriers in any suitable manner.

Any suitable means may be provided for operating the rug carriers, such as an electric motor, but in the drawings means for manual operation is shown. The drive shafts 16 located in the lower front portion of the cabinet have their outer ends projecting

through one side of the casing and these ends are squared as at 27 to receive a suitable detachable crank-handle 28. When the handle is turned to convey a rug from its stored to exhibiting position, or returned to its stored position, a chain and gear connection is employed for each of the rug carriers as shown in Figures 3 and 4. In moving through the cabinet the carrier travels over 10 the upper sprockets and under the lower sprockets 19, and to provide for this operation a gear 29 is mounted on the drive shaft 16 adjacent its end. This gear is in mesh with a gear 30 mounted on a stud shaft 31 15 secured to the side frame of the cabinet. A sprocket 32 is also mounted on the stud shaft 31 and is secured to the gear 30, and sprocket 33 is mounted on the shaft 17. Over the respective pair of lower and upper sprockets 20 32 and 33 a sprocket-chain 34 travels and transmits power from the drive shaft 16, and gears 29 and 30 to the driven shaft 17 for operating the rug carriers when the crank handle is turned.

25 The upright portion of the cabinet may be closed at its front by means of a curtain 35, herein shown of the spring actuated roll type, secured by brackets 36 to the front top portion of the cabinet.

30 While a series of only four rug carriers are shown, a larger number are employed so that the cabinet may contain a larger variety of rugs for a prospective purchaser to select from. In exhibiting a rug for display, the 35 salesman turns the crank handle toward the right, which causes the carrier to first withdraw a rug from the storage compartment. During its travel the carrier is guided across the top of the cabinet and then down into the 40 first display section where the rug is exhibited in a vertical position. A further operation of the handle then causes the carrier to travel in its guides to the second display section where the rug is exhibited in a horizontal position. To return the rug to the 45 storage compartment, the crank-handle is operated in a reverse manner.

It is obvious that certain changes may be made in details of construction and arrangement of parts without departing from the 50 spirit of the invention, and therefore I do not wish to be limited to such features, except as may be required by the claims.

55 What is claimed is:—

1. In a display cabinet for rugs and other textile fabrics, the combination of a casing having vertically arranged sections one of said sections providing a rear storage compartment and the other providing an open front display compartment, a plurality of independently operable rug carriers, each of which is adapted to support a rug in extended position, said rug carriers being mounted in 60 said casing and adapted to travel in said com-

partments and means for operating the carriers.

2. In a display cabinet for rugs and other textile fabrics, the combination of a casing having vertically arranged sections one of 70 said sections providing a rear storage compartment and the other providing an open front display compartment, guides mounted in said compartments, a plurality of independently operable rug carriers, each of 75 which is adapted to support a rug in extended position, said rug carriers being mounted in said casing and adapted to travel in said guides and means for operating the carriers.

80 3. In a display cabinet for rugs and other textile fabrics, the combination of a casing having an open top horizontal display section and an open front vertical display section, a plurality of independently operable rug carriers, each of which is adapted to support a rug in extended position, said rug carriers being mounted in said casing and adapted to travel in said display sections and means for operating the carriers.

85 4. In a display cabinet for rugs and other textile fabrics, the combination of a casing having an open top horizontal display section and an open front vertical display section, guides mounted in said sections, a plurality of independently operable rug carriers, each of 90 which is adapted to support a rug in extended position, said rug carriers being mounted in said casing and adapted to travel in said guides and means for operating the carriers.

95 5. In a display cabinet for rugs and other textile fabrics, the combination of a casing having an open top horizontal display section and an open front vertical display section, said vertical section also provided with a 100 storage compartment, a plurality of independently operable rug carriers, each of which is adapted to support a rug in extended position, said rug carriers being mounted in said casing and adapted to travel in said display sections and storage compartment and means for operating the carriers.

105 6. In a display cabinet for rugs and other textile fabrics, the combination of a casing having an open top horizontal display section and an open front vertical display section, said vertical section also provided with a storage compartment, guides secured to the inner opposite sides of said sections and storage compartment, a plurality of independently operable rug carriers each of which 110 is adapted to support a rug in extended position, said rug carriers being mounted in said casing and adapted to travel in said guides and means for operating the carriers.

115 7. In a display cabinet for rugs and other textile fabrics, the combination of a casing having a storage compartment and an open front display compartment, guides mounted in said casing, sprocket wheels mounted on 120

125

- the inner opposite sides of said casing, a plurality of independently operable rug carriers mounted in the casing, each of which comprises a series of cross-bars and chains mounted on the ends of said bars for travelling over the sprockets, each of said carriers adapted to support a rug in extended position and to travel in said guides and means for operating the carriers.
8. In a display cabinet for rugs and other textile fabrics, the combination of a casing having an open top horizontal display section and an open front vertical display section, said vertical section provided with a storage compartment, guides mounted in said casing, sprocket wheels mounted on the inner opposite sides of said casing, a plurality of independently operable rug carriers, mounted in the casing, each of which comprises a series of cross-bars and chains mounted on the ends of the bars for travelling over said sprockets, each of said carriers adapted to support a rug in extended position and to travel in said guides and means for operating the carriers.
- 20 In testimony whereof I have affixed my signature.

ALFRED J. MURPHY.
